ATTORNEY

UNITED STATES PATENT OFFICE.

RAYMOND RASBACH, OF HERKIMER, NEW YORK.

SEWING-MACHINE.

1,082,819.

Specification of Letters Patent. Patented Dec. 30, 1913.

Application filed May 10, 1913. Serial No. 766,700.

To all whom it may concern:

Be it known that I, RAYMOND RASBACH, a citizen of the United States, residing at 305 King street, Herkimer, in the county of 5 Herkimer and State of New York, have invented certain new and useful Improvements in Sewing-Machines, of which the following is a specification, reference being had therein to the accompanying drawing.

10 My invention relates to an improvement in sewing machines, and I declare that the following is a full, clear, concise and exact description thereof, sufficient to enable one skilled in the art, to make and use the same, 15 reference being had to the accompanying drawings in which like characters refer to like parts throughout.

The invention is shown as applied to a 20 Merrow sewing machine although it is equally applicable to other machines, where a moving part reciprocates on a given base.

In the drawings, Figure 1 has a front view of the face plate or frame-cap of a machine. Fig. 2, is a rear view of the same. 25 Fig. 3, is a similar view with parts removed; while Fig. 4, is an end view.

Referring to the figures in detail, 1 represents the face plate or work plate which has an aperture at 2 for the travel to and fro 30 therein of the thread eye 3, which is carried on the block 4 mounted on the rear or face of the plate. The block 4, is held against the plate by the beveled edge pieces 5 and 6, the edge of the block 4 being correspondingly beveled so said pieces slide to and fro, but are held to the plate 1, and in course of time, wear the same so that there would be looseness in the play of the parts and plate 1 would become worn so far as to require 35 replacing. In order to avoid that necessity, I cut out the plate to form two square grooves, lengthwise the line of travel of block 4; in which I place bearing blocks 8 and 9, which are square in cross-section and are made particularly to sustain the wear 40 of the block 4. As one edge of each of these blocks becomes worn the block may

be removed from its groove, turned quarter way around and replaced so that a new wearing surface is provided. This adjustment may be continued until each of the four surfaces has been used. After this, it may be turned end for end, and the same course followed in presenting different faces to the wear of the block, since the block 5 travels only about half of the distance across the plate, the major part of the wear, coming upon one-half the length of the block.

Having described my invention, which I claim as new and desire to secure by Letters Patent, is:

1. In a sewing machine, a face-plate having grooves cut therein, rectangular in cross section, and bearing-bars, rectangular in cross-section, placed in said grooves and 65 being interchangeable to present any of four faces.

2. In a sewing machine, the combination of a face-plate having an aperture cut for the travel of a sewing mechanism therein 70 and having grooves rectangular in cross-section cut alongside the aforementioned aperture, and bearing-bars loosely mounted in the said grooves and interchangeable end for end to take the wear of the said sewing mechanism.

3. In a device of the character described, a plate having an aperture for the movement of a traveling mechanism, the plate having a groove rectangular in cross-section 80 and lengthwise of the travel of said mechanism, and a bar adapted for the support of the traveling mechanism and adapted to be converted end for end and to present any of four surfaces to the said mechanism 85 whereby such bar may be placed to present any of eight wearing surfaces to the wear of said mechanism.

In testimony whereof I hereunto affix my signature in the presence of two witnesses. 90

RAYMOND RASBACH.
